WINDOW OPERATOR CONSTRUCTION

Matt Gzupkaytii, Miami, Fla.

Application March 22, 1949, Serial No. 82,723

3 Claims. (Cl. 268—123)

1

This invention relates to window constructions for residential, commercial or industrial structures and more particularly to a device comprising one or more sash, arranged in a vertical series if a plurality of sash are employed, the sash being pivoted for angular movement about a horizontal axis or axes, and adapted to be actuated automatically to closed position during a rainfall, and to be automatically opened again after the rain has ceased. Another feature of the present invention provides for manually operated mechanical actuating means for the sash, together with clutch means for selectively engaging and disengaging such actuating means from the sash, so that the latter may be conditioned either for manual or automatic operation as desired.

It has been proposed heretofore to adapt window sash for actuation to a closed position by employing the weight of accumulated rain water, but such previous proposals have been impractical in design and construction, and have not gone into use. Accordingly, it is the principal object of the present invention to provide a rain-operated window which is essentially conventional in appearance yet is adapted for automatic operation in a very simple and practical manner.

Another object of the invention is to provide a window of the type described, in combination with manually operated mechanical actuating means including a clutch device, whereby the sash may be mechanically actuated or, in the alternative, released from the mechanical actuating mechanism so as to be fully automatic in operation.

Another object of the invention is to provide a construction in which a plurality of sash, of the type described, are arranged in vertical series and interconnected in such a way that all sash of the series may be actuated by manual operation of a single crank or equivalent device.

Other and further objects, features and advantages will be apparent from the description which follows, read in connection with the accompanying drawings in which

Figure 1 is a front elevational view of a vertical series of three sash, constructed according to the invention;

Figure 2 is a vertical section on line 2—2 of Figure 1;

Figure 2a is a vertical section illustrating the manner of seating of the lower member of each sash against the upper member of the next lower sash.

Figure 2b is a vertical section illustrating in detail the construction of a portion of the upper horizontal member of each sash.

Figure 3 is a partial vertical section on line 3—3 of Figure 2;

Figure 4 is an enlarged detailed view, in perspective and exploded, of the mechanical actuating means;

Figure 5 is a horizontal section on line 5—5 of Figure 3;

Figure 6 is a vertical section on line 6—6 of Figure 1;

Figure 7 is a vertical section on line 7—7 of Figure 2;

Figure 8 is an enlarged detailed view, in section, of a portion of the clutching mechanism;

Figure 9 is a front elevational view illustrating a modification of the invention;

Figure 10 is a side elevation corresponding to Figure 9;

Figure 11 is a horizontal section on line 11—11 of Figure 10; and

Figure 12 illustrates a modification of an element of the linkage illustrated in Figure 10.

In order to facilitate an understanding of the invention, reference is made to the embodiment thereof shown in the accompanying drawings and detailed descriptive language is employed. It will nevertheless be understood that no limitation of the invention is thereby intended and that various changes and alterations are contemplated such as would ordinarily occur to one skilled in the art to which the invention relates.

Referring to Figures 1 and 2, the invention comprises generally a window frame consisting of vertical members 10 and 11, top member 12 and bottom member or sill 13, and a plurality of sash 14 mounted therein. Each of the sash 14 is preferably rectangular in shape and also comprises vertical side members 15 and 16, a top member 17 and a bottom member 18. Both window frame and sash are preferably constructed of metal, such as sheet steel or aluminum, the several members being joined together by bolting or welding, or in any other suitable or conventional manner. The top member of each sash is formed with an upstanding flange 19 extending laterally throughout the length of its rearward upper edge, the said flange of the uppermost member being adapted to seat against the rearwardly directed surface of the top member 12 of the frame, and the said flanges of the remaining sash being adapted to provide seats for the lower members 18 of the next higher sash. As seen in Figure 2b the flange 19 of the upper horizontal member of each sash is provided with a resilient metal weatherstrip 19' and the bottom member 18 of each sash is formed with a recess 18' extending across its lower inner

45
50
55

corner to accommodate the flange 19 and weatherstrip 19' in seating against the next lower sash.

Conveniently, the bottom, top and side members of the respective sash are made hollow to minimize the weight of the sash and to conserve metal and decrease the cost thereof, but the side and upper members may, if desired, be of wooden or other solid construction. The lower member 18, however, is made of hollow construction for reasons set forth below. All of the structural members of the sash are preferably provided with approximately centrally located grooves extending longitudinally thereof for the reception of a pane of glass 20, which is secured in the socket thus provided by means of putty, cement, rubber molding strips, or in any suitable manner. The pane 20 is, of course, secured in place during assembly of the sash since, in the present construction, the pane may not be put in position after the structural members are assembled together.

Each of the sash 14 is provided near the upper ends of its respective side members 15 and 16, and secured to the inward surface thereof, with an arm or lever 21 which is bolted or otherwise secured to the sash member and, slightly above the top surface of each sash member, with a laterally extending pivot 22 (Figure 7) by means of which the sash is pivotally mounted in sockets provided in the adjacent frame members 10, 11. The inwardly extending end of each arm 21 is pivotally connected to a vertical series of links 23, which are conveniently connected together by means of the same pivot pins by which the arms 21 are connected thereto. The lowermost link 23 is pivotally connected to arms 24a and 24b secured upon a horizontal shaft 25 extending transversely of the window frame adjacent the sill and mounted, at one end, in a bearing provided in a block 26 secured to the adjacent side frame member and, at the other end, supported in a bearing formed centrally of the worm wheel 27. The shaft 25 is biased toward the right in Figure 3 by means of spring 28.

The worm wheel 27 is mounted on a trunnion 29 formed on the back plate 30 of a casing 31 bolted or otherwise suitably secured to the side frame member 11, the adjacent end of the shaft 5 extending through an aperture in the back plate 30 and being rounded as at 32. Interposed between the end 32 of the shaft 5, and the adjacent side frame member 11, is a clutch operating member 33 (Figure 5) provided with a circular recess 34 having inclined sides, for receiving the end 32 of the shaft when the latter is to be mechanically actuated. The clutch actuating member 33 is provided with a slot 35 in which is engaged a headed stud 36 secured in the adjacent side frame member, the member 33 being thus operable toward and away from the sash so as to cam the shaft 5 to the left, or permit it to move to the right under the pressure of the spring 28.

As best seen in Figure 4, the arm 24a at that end of the shaft adjacent the worm wheel 27 is provided with two studs or projections 37 adapted to engage in complementary sockets 38, preferably four in number, formed in the projecting end of the worm wheel 27. The latter is retained in the casing 31 by means of an annular flange 39 formed on the outer end of the worm wheel and adapted to be retained in operative position by means of a strap 40 secured to the adjacent wall of the casing 31.

When the studs 37 are within a diametrically

opposed pair of sockets 38 of the worm wheel 27, the arm 24a is, of course, operatively connected with the worm wheel whereas, when the shaft 5 is moved to the left as by actuation of the clutch operating member 33, the studs 37 are withdrawn from the sockets 38 and the arm 24a, shaft 5, and connected linkage are disconnected from the worm wheel 27.

The worm wheel 27 is in mesh with a worm 10 41 secured upon the shaft 42, the outer end of which is provided with a crank 43 for manual operation, the shaft 42 being journaled in any suitable manner in the casing 31.

Referring now to Figure 2, it will be seen that, 15 when the linkage comprising the arms 21 and links 23 is disconnected from the mechanical actuating means, as described, it serves as a counterbalance for the sash 14 and will cause them, through the action of gravity, to assume an inclined position, for example as illustrated 20 in Figure 2. The inclination of the arms 21, and the weights of the sash on the one hand and linkage on the other hand, may be designed so that the sash will be balanced in the desired inclined position. Also, if desired, the construction may be so designed that the lower end of the lowermost link 23 will engage the sill 13 to provide a stop for the opening movements of the sash.

As best seen in Figure 6, the lower member 18 of each sash is made hollow, and is provided with apertures 44 in that portion of its upper side which lies on that side of the pane 20 which is outside the building. One or more smaller apertures 45 are formed in the lower part of the member 18, the total area of the aperture or apertures 44 being in excess of the total area of the aperture or apertures 45. Thus, when the sash are declutched from the mechanical actuating means, and are in an inclined position such as illustrated in broken lines in Figure 2, if rain commences to fall, the drops falling upon the panes 20 of the respective sash will be collected within the hollow interior of the bottom members 18, and as the weight of the collected water increases, the sash will be caused to swing downwardly about the pivots 22 to a closed or nearly closed position, the counterbalancing weight of the linkage 21, 23 being overcome by the increased weight of the lower sash members.

The water collected within the bottom sash members 18 will, of course, escape slowly through the apertures 45, but at such a rate that the water will not be completely discharged from the members 18 until the rainfall has diminished to such an extent that it is again permissible for the sash to assume their open or inclined positions.

On the other hand, when automatic operation is not desired, the clutch operating member 33 is pushed toward the sash permitting the shaft 5 to move to the right into the socket 37 and engaging the clutch 37, 38, enabling the entire series of sash to be manually operated through the medium of the crank 43.

From the foregoing description it will be appreciated that the invention provides a simple and inexpensive automatic window construction, together with declutchable mechanical actuating means, either automatic or manual operation being adapted to control any reasonable number of sash arranged in a vertical series.

The modification illustrated in Figures 9-11 differs from that heretofore described in that the vertical series of sash is divided into two

groups 50 and 51, the sash of each group being interconnected by means of a linkage 52, 53, respectively, and being operable by means of separate actuators 54 and 55. As in the previous case, the actuators are clutch-connected to the linkages, so that each group of sash may be operated either manually or automatically, as desired, and independently of the other group. This arrangement is advantageous in that it permits one group of sash to be opened and the other to be kept closed, when desired, the open group being adapted either for automatic or for manual actuation.

Another feature illustrated in Figures 9-11 consists in arranging the linkages 52 and 53 laterally outside of the window frame or window opening proper and between the outer and inner wall flanges of the window frame so that they will be concealed when the structure is incorporated in a building. The construction and operation of the linkages is essentially the same as in the case of Figures 1-8, inclusive, except that each sash 50, 51 is connected with its operating arm 56 through the intermediary of a spindle 57 which extends through and between the opposite vertical members of the window frame, the sash being secured to the spindles 57 by means of brackets 58. If desired, the straight arm 56' illustrated in Figure 12 may be substituted for the arms 56 of Figure 10.

Having thus described the invention, what is claimed as new and desired to be secured by Letters Patent is:

1. In a window device, a window frame, a sash pivotally supported in said frame for angular movement about a horizontal axis, said sash including a hollow bottom member adapted to receive rain water therein and having at least one escape aperture in its bottom portion, the area open for the reception of water at the top of said

member exceeding the area of said escape aperture, counterbalance means associated with said sash and normally balancing said sash in an inclined position relative to said frame, and crank operated mechanism for moving said sash about said axis, including manually controlled clutch means between said crank and said sash for selectively operatively connecting and disconnecting the same.

- 10 2. The combination defined in claim 1, said crank operated mechanism including a shaft, a lever on said shaft and operatively connected to said sash, a worm wheel, a worm meshing with said worm wheel and operatively connected with said crank, and clutch means for selectively engaging and disengaging said worm wheel and said lever.
- 15 3. The combination defined in claim 2, said clutch means comprising manually operable means for moving said shaft endwise for engaging and disengaging said worm wheel and lever.

MATT GZUPKAYTIL.
